(57) **CLAIM**

The ornamental design for a food tray, as shown and described.

DESCRIPTION

FIG. 1 is a front perspective view of a food tray showing the new design;

FIG. 2 is a top side elevational view thereof;

FIG. 3 is a bottom side elevational view thereof;

FIG. 4 is a right side elevational view thereof;

FIG. 5 is a left side elevational view thereof;

FIG. 6 is a top side elevational view thereof; and,

FIG. 7 is a bottom side elevational view thereof.

The broken lines are for the purpose of illustrating the environment of the design only and form no part of the claimed design.
